UNITED STATES PATENT OFFICE.

WILLIAM WILKINSON, OF WIGAN, COUNTY OF LANCASTER, ENGLAND.

TRAMWAY-LOCOMOTIVE.

SPECIFICATION forming part of Letters Patent No. 276,948, dated May 1, 1883.

Application filed May 18, 1882. (No model.) Patented in England October 1, 1881, No. 4,268.

To all whom it may concern:

Be it known that I, WILLIAM WILKINSON, of Wigan, in the county of Lancaster, England, have invented a new and useful Improvement 5 in Tramway-Locomotives, of which the following is a specification.

The general object of my invention is to effect a combination of mechanical contrivances in a tramway-locomotive whereby the steam- 10 motor shall be rendered less an object of terror to timid persons and animals in the streets of cities.

This invention consists in certain novel combinations of parts which have been united with 15 other parts in a tramway-locomotive to accomplish the aforesaid object, as hereinafter described and claimed.

In the drawings which accompany this specification, Figure 1 is a sectional side elevation of my improved tramway-locomotive. Fig. 2 is a transverse section of the same, and Fig. 3 is another side elevation thereof.

In order to render the locomotive small and compact, an upright or vertical boiler fitted 20 with what are known as "Field's Patent Tubes" has been adopted as the basis of this locomotive, the same being mounted on suitable framing, with track-wheels and other accessories which do not require particular mention.

Two inverted direct-acting cylinders, A, drive two cranks, B, at right angles one to the other. The crank-shafts are rigidly attached to the framing of the engine, and are fitted with a gun-metal, wrought-iron, or steel spur-wheel, C, gearing with a second spur-wheel, D, keyed on the driving-axle S, on which are keyed the driving-wheels to run on the tram-rails. These wheels may be coupled to the trailing or leading wheels, or to both, if required. By this method of connection of engines to driving-wheels I obviate "galloping," or a jumping action of the locomotive on the road, that would take place if the engine were connected with the driving-wheel axle directly.

Two jackets, E, made from wrought or cast iron or other suitable material, are fixed one on each side of the boiler F, and closely attached thereto, so as to be heated to the same temperature as the boiler. The steam from 40 the cylinders A is exhausted into these jack-

ets and there heated, any water that may have passed over with the said exhaust-steam being thereby intercepted and partially evaporated. From these jackets are led two pipes, G, passing into and down the inside of the uptake or chimney of the furnace, into a vessel, H, made from cast-iron or any suitable material, suspended inside the furnace at any convenient distance below the foot of the uptake, and acting as a distributor of the heated gases among 55 the tubes. From this vessel an enlarged pipe, I, is led vertically any convenient distance up the uptake, directing the waste steam up the chimney in a dry and superheated state, invisible to the eye, while it increases the draft 60 of the furnace in the usual manner.

The before-mentioned vessel H, into which the waste or exhaust steam is finally led, being exposed to the greatest heat of the furnace J, effectually superheats and dries the steam, 70 so that no water can be emitted from the funnel, and owing to the steam being expanded in two separate vessels after leaving the cylinders of the engine the pressure is thereby so much reduced as to decrease to a minimum the 75 noise of the exhaust-steam when reaching the air.

The safety-valves are inclosed in a box, T, Figs. 1 and 3, from which two pipes, T², are led, one into each of the jackets E, in order to 80 reduce to a minimum the noise resulting from blowing off steam from overpressure. The waste-pipes U, Figs. 1 and 3, from the cylinders are also led into the jackets E, thereby preventing any noise of escape when the engine is starting on a journey, with the cylinder-cocks open for the discharge of water from the cylinders. All water led into or produced 85 by condensation within the before-mentioned side jackets is led therefrom by pipes V, Figs. 90 1 and 3, into a steam and water tight tank, R, which may be carried on any convenient part of the locomotive, and which can be emptied at will.

To control and equalize the speed of the locomotive a governor is employed, preferably of the class known as "Allen's Paddle-Governors," as indicated by its pulleys and driving-band at S S² S³, Fig. 3, to reverse the valve-gear and apply the brakes when a given speed 95 100 is reached.

is attained. This is effected by means of an eccentric cam, K, with a lever-motion, which opens a valve against the boiler-pressure, thereby allowing the water or steam to pass through 5 a pipe to the under side of one or more pistons or hydraulic rams in direct communication with the reversing-shaft L and brake-shaft M, reversing the engines and applying the brakes at one and the same time and automatically. In the under side of the hydraulic or steam cylinders before mentioned, containing the pistons or rams N, it is proposed to fix taps or cocks and pipes, which can be used for regulating the outflow of the steam or water after 10 reversing the engine. The connection between each ram or piston N and the reversing-shaft L is made by means of a slotted link, O, of such kind that the engine can be reversed in the usual manner by hand without moving the 15 said ram or piston; but the said pistons cannot be moved without reversing the engine. The same kind of slotted connection is introduced between said pistons N and the brake-shaft M to provide for applying the brakes by 20 hand or foot in the usual manner.

In the ordinary field-boiler the portion of the uptake or chimney which passes through the steam-space above the water-line inside the boiler is liable to have scale and hard mud 30 formed upon it by reason of the scum floating on the surface of the water becoming baked and attached thereto, and this at times, dropping off and choking or fouling the circulating-tubes, interferes with the effectual circulation 35 of the water, thereby causing the tubes to burn out. To obviate this a disk, Q, of iron, copper, or other suitable material, is fitted onto the uptake P inside the boiler, so as to catch and intercept any scale that may be 40 formed and prevent it falling into the tubes. The chimney or uptake, passing through the steam-space, as aforesaid, is subject to a very high temperature, and invariably wastes away very much more rapidly at this point than at 45 any other portion of the boiler. This part is protected, then, by fitting a wrought-iron or other suitable casing, R, inside the uptake, where the same passes through and above the water-line of the boiler. An annular space is 50 left inside the casing, which may be packed with fire-clay or other non-conducting and fire-resisting material; or the space may, if desired, be left vacant.

I do not claim herein the said scale and mud shield and uptake-casing, but disclaim the 55 same, as no part of my present invention, in favor of a separate application for patent, filed the 2d day of March, 1883; neither do I claim herein the said combination of automatic governor, steam or hydraulic brake, and valve- 60 reversing gear, nor any part of the same, but hereby reserve the right to claim the same in a future application for patent.

What I claim as novel, and desire to protect by Letters Patent, is—

1. The combination, in a tramway-locomotive, of chambers or jackets attached to the boiler, pipes conducting escape-steam thereto, and pipes leading down the uptake or funnel into another vessel placed in the furnace, immediately at the foot of the uptake, to expose the escaping steam to the direct heat of the furnace for drying and superheating it before its escape into the air to render it invisible, substantially as herein specified.

2. The combination, in a tramway-locomotive, of chambers or jackets attached to the boiler, pipes conducting escape-steam thereto, and pipes leading from said chambers or jackets to another chamber, within which the steam 80 is expanded a second time before it escapes, substantially as herein specified, to reduce the noise of escaping steam.

3. The combination, in a tramway-locomotive, of chambers or jackets attached to the 85 boiler, pipes leading from the waste-cocks of the engine-cylinders thereto, and pipes leading from said chambers or jackets to another chamber, within which the steam is expanded a second time before it escapes, substantially 90 as herein specified, to prevent noise from escape at said cylinder waste-cocks.

4. The combination, in a tramway-locomotive, of chambers or jackets attached to the boiler, pipes conducting escape-steam and 95 water thereto, and pipes leading from said chambers or jackets to a water-tight settling-tank, which collects the separated water, substantially as herein specified, as means for preventing the escape of water.

London, April 1, 1882.

WM. WILKINSON.
